Primary Examiner — Ryan Harvey(74) *Attorney, Agent, or Firm* — John Rizvi; The Patent Professor ®(57) **CLAIM**

I claim the ornamental design for an exercise apparatus, as shown and described.

DESCRIPTION

FIG. 1 is a top, front right-side isometric view of an exercise apparatus showing my new design;

FIG. 2 is a bottom, front left-side isometric view thereof;

FIG. 3 is a front elevation view thereof;

FIG. 4 is a top plan view thereof;

FIG. 5 is a bottom plan view thereof;

FIG. 6 is an enlarged, left side elevation view thereof; and, FIG. 7 is an enlarged, right side elevation view thereof.

A design rear elevation view has been omitted, as it is a mirror image of the front elevation view of FIG. 3.

The portions of the exercise apparatus depicted in the figures in broken lines form no part of the claimed design.
